UNITED STATES PATENT OFFICE.

CLAUDE JOSEPH OLLAGNIER, OF TOURS, FRANCE.

MACHINE FOR PULPING APPLES, PEARS, &c.

SPECIFICATION forming part of Letters Patent No. 531,058, dated December 18, 1894.

Application filed May 4, 1893. Renewed October 6, 1894. Serial No. 525,090. (No model.) Patented in France October 22, 1892, No. 224,994.

To all whom it may concern:

Be it known that I, CLAUDE JOSEPH OLLAGNIER, a citizen of the French Republic, residing at Tours, France, have invented certain new and useful Improvements in Machines for Pulping Apples, Pears, &c., (for which I have obtained a patent in France, dated October 22, 1892, No. 224,994,) of which the following is a description.

10 My invention has for its object a novel pulping machine for apples, pears, &c., that will make a thoroughly fine pulp, not crushed, and whereby the skin of the fruit remains nearly whole, the seeds are not crushed and 15 stones or hard substances that may be found between the fruit will be easily removed.

In order to better explain the mechanism and working of my machine, I have illustrated the same in the annexed drawings, which 20 make part of this specification, and wherein—

Figure 1 shows a vertical section of the machine on the line $x-x$ of Fig. 2, and Fig. 2 shows a side view of the machine.

A glance at the drawings shows that the machine consists essentially of four pistons, 25 coupled together two by two, by means of rods a , one couple of these pistons $C C'$ moving in a direction at right angles to the motion of the other couple. These pistons are equipped at their inside with a friction roller c , running on the periphery of a stationary cam E . The rotating drum F is provided with four apertures f , wherein the pistons are moving outward and inward in accordance with the sinuosities of the cam E . These 35 parts are located in a casing G , provided with longitudinal slots e and with an opening T for the discharge of stones. The casing G is connected with the hopper K wherein the apples that are to be pulped, are fed.

The cam E is rigidly mounted upon a shaft L , that is provided at its end with a tappet M , that rests upon the nose i of a weighted lever N , which lever is pivoted at O . The 45 last described parts are located outside the casing G .

The operation of the apparatus is as follows: The hopper K is filled with apples, pears, &c., which will drop down into the

apertures f , as they successively pass under the hopper. The friction rollers c , running over the periphery of the cam E , will set the pistons C, C', D, D' in motion and advance them toward the walls of the casing G and thus subject the apples contained between the piston and the wall to a strong pressure. The juice of the fruit is discharged through the slots e provided for that purpose. The rotary motion of the drum F is imparted by a fly-wheel P , if the apparatus is worked by hand, or a pulley, if worked by power. The purpose of the tappet M and of the weighted lever N is to automatically stop the operation of the apparatus if by some accident a stone or any other hard body should be between the apples. To this effect the lever N is weighted to overcome a certain pressure, but if the pressure becomes too strong, *i.e.* if a hard object should have found its way between the piston and the wall of the casing, 70 this object will act as a wedge and the cam E will be carried along. Thus the motion will be communicated to the tappet M , that will effect a pressure upon the nose i of the weighted lever N which will be raised until 75 the nose i will be released by the tappet. The cam E and the drum F rotate then together and the obstacle is discharged at the opening T .

Having now described my invention, what 80 I claim as new, and desire to secure by Letters Patent, is—

1. In a fruit pulping machine, the combination with a circular casing, of a rotary drum located therein, movable pistons adapted to 85 be actuated at right angles to the axis of the drum located within the same, a normally stationary cam adapted to actuate the pistons so as to receive the fruit, compress it against the casing and discharge the same, as the 90 drum is rotated, and means for normally holding the cam against rotation and for automatically releasing the same when any of the pistons meet with more than a predetermined resistance, substantially as shown and described. 95

2. In a fruit pulping machine, the combination with a circular casing, of a rotary drum

- located therein, a series of movable pistons located within the drum at substantially right angles to the axis thereof, a cam rigidly mounted upon a shaft and adapted to actuate the pistons so as to receive, and compress the fruit against the casing, and discharge the same, as the drum is rotated, a weighted lever, and a tappet rigidly mounted upon the cam shaft and engaging with the weighted lever; the construction being such that the weighted end of the lever will be lifted and the cam rotated with the drum when any of the pistons meet with more than a certain resistance, substantially as described.
- 15 3. In a fruit pulping machine, the combination with a circular casing provided with openings or perforations *e* in the encircling wall thereof, of a rotary drum located therein, movable pistons adapted to be actuated at right angles to the axis of the drum located within the same, and a stationary cam adapted to actuate the pistons as the drum is rotated so as to compress the fruit against the casing adjacent to the openings *e*, substantially as shown and described.
- 20 4. In a fruit pulping machine, the combination with a circular casing having a feed opening *K*, and a discharge opening *T*, and provided with openings or perforations *e* in the periphery of the casing between the feed and discharge openings, of a rotary drum located therein, movable pistons adapted to be actuated at right angles to the axis of the drum located within the same, and a stationary cam adapted to actuate the pistons so as to receive the fruit, compress it against the casing adjacent to the openings *e*, and discharge the pulp through the opening *T*, as the drum is rotated, substantially as shown and described.

5. In a fruit pulping machine, the combination with a circular casing provided with openings or perforations *e*, and with feed and discharge openings *K* and *T*, of a drum *F* provided with passages *f* located at right angles to each other and to the axis of the drum, 45 pistons *C* and *C'*, and *D* and *D'*, located in the passages *f* and secured together so as to be actuated in pairs, means for rotating the drum, means for actuating the pistons so as to receive, and compress the fruit and discharge the pulp as the drum is rotated, and means for preventing more than a certain pressure from being exerted by the pistons, substantially as shown and described.

6. In a fruit pulping machine, the combination with a circular casing provided with openings or perforations *e*, and with feed and discharge openings *K* and *T*, of a drum *F*, provided with passages *f* located at right angles to each other and to the axis of the drum, 60 pistons *C* and *C'*, and *D* and *D'*, located in the passages *f* and secured together so as to be actuated in pairs, means for rotating the drum, a cam *E*, rigidly mounted upon a revolute shaft *L*, and located within the drum 65 and adapted to actuate the pistons as the drum is rotated, a tappet *M* rigidly secured to the shaft *L*, and a weighted lever *N*, engaging the end of the tappet *M*, in such manner as to normally prevent the rotation of the shaft *L*, substantially as shown and described.

In testimony that I claim the foregoing I have hereunto set my hand this 12th day of March, 1893.

CLAUDE JOSEPH OLLAGNIER.
